UNITED STATES PATENT OFFICE.

JOHN KRALUND AND CLARENCE H. DUCKWORTH, OF BROOKLYN, NEW YORK,
ASSIGNORS TO DOEHLER DIE CASTING COMPANY, OF BROOKLYN, NEW
YORK, A CORPORATION OF NEW YORK.

DIE-CASTING APPARATUS.

Application filed May 8, 1920. Serial No. 379,711.

To all whom it may concern:

Be it known that we, JOHN KRALUND and CLARENCE H. DUCKWORTH, both citizens of the United States, and both residing in the 5 borough of Brooklyn, in the city of New York, county of Kings, and State of New York, have invented certain new and useful Improvements in Die-Casting Apparatus, of which the following is a specification.

10 Our invention relates to die casting apparatus and particularly to improvements in the mechanism for supplying molten metal from a melting pot to a suitable die or mold by air or other gaseous pressure. By our 15 invention, a movable member, which may be termed a carrier or ladle, is made use of, the mechanism being so arranged that the nozzle or mouth-piece of this device is first immersed in the molten metal so that a 20 charge of the same runs into its interior, after which the carrier is moved to cause its mouth to align accurately with the gate or opening of the die. As soon as this is accomplished compressed air or other suitable gas 25 is forced through the carrier to deliver the charge of metal into the die.

In Patent No. 1,299,738, granted April 8, 1919, to John Kralund, a carrier or ladle is made use of which has a swinging movement 30 and also moves bodily, laterally of the melting pot, to take the charge of molten metal and deliver the same to the gate opening of the die. According to our present invention the carrier does not have a swinging movement. Broadly speaking we provide means 35 for causing relative bodily movement between the carrier device and melting pot, in a vertical direction, to submerge the mouth of the carrier device in the molten metal 40 and to uncover the same, and mechanism for causing relative bodily movement between the melting pot and the carrier device in a horizontal direction to place the mouth of the carrier device in delivery position and to 45 return the same into position to be submerged within the molten metal.

In our preferred construction the melting pot itself is vertically movable so that in the operation of the device the melting pot 50 is first raised to immerse the mouth piece of the carrier beneath the surface of the molten metal so that the charge will flow into the interior of the carrier. The melting pot is

then lowered, after which the carrier is moved horizontally into registration with 55 the die, whereupon pressure is applied to force the charge into the die, and the carrier moved back to its former position, after which the cycle of operations is repeated for each casting.

The object of our invention is to provide effective devices of the character described. The carrier may be caused to run on horizontal tracks, being operated by a hand lever or similar means, with which a toggle joint 60 may effectively be used to lock the carrier in the position in which it delivers the charge into the gate opening of the die. The melting pot may readily be raised and lowered by means of a hand lever or the like with 65 which a toggle joint may effectively be used to lock the melting pot in its raised position in which the charge is taken into the carrier through the mouth piece.

In order that our invention may be more 75 clearly understood attention is hereby directed to the accompanying drawings forming part of this application and illustrating one embodiment of our invention. In the drawings Fig. 1 represents a view partly in 80 side elevation and partly in section of a form of apparatus embodying our invention and Fig. 2 represents a top plan view of the same.

Referring to the drawings the melting pot 85 1 is adapted to contain a substantial body of molten metal and is heated by any usual heating means (not shown) in the heating chamber 2. The melting pot is supported by a vertical plunger 3 which is mounted to 90 slidably extend through an opening in the bottom of the heating chamber 2. The plunger 3 is supported from a pair of toggle links 4 and 5, the latter of which is secured at its lower end to a shaft 6 mounted in a 95 support 7 which may rest on the floor. The heating chamber 2 may be supported by any suitable means, which I have not deemed it necessary to show.

The melting pot is provided with pins 8, 100 9, which are slidably mounted in guideways 10 which are formed on the inner side surface of the heating chamber 2 so as to insure a straight line rise and fall of the melting pot. A hand lever 10 is secured to shaft 6 105 so that by the operation of the same the tog-

gle links 4 and 5 will be straightened to raise the melting pot, and will be broken to lower the melting pot. When the melting pot is in its raised position, the links 4 and 5 will be in vertical alignment with each other so as to hold or lock the melting pot in its raised position until the toggle is broken by swinging the hand lever 10.

The carrier device 11 is preferably of the 10 goose-neck shape indicated and is provided on its forward end with a mouth or nozzle 12. The interior of the device is hollow and adapted to contain a suitable charge of molten metal. A pipe connection 13 leads 15 into the closed rear end of the device for the purpose of carrying compressed air or other gas, when the air connection is open, for forcing the charge of molten metal in the carrier device out from the nozzle 12.

20. We have indicated at 14 a frame for carrying the die, this frame having an end plate 15 through which extends a horizontal opening provided with a bushing the end of which is indicated at 16. The forward half 25 of the die is adapted to be mounted against the plate 15 with the opening in which bushing 16 is mounted communicating with the interior of the die and forming a gate opening therefor. In operation, the frame 30 14 is so positioned that end plate 15 will be closely adjacent to the heating chamber 2 with the end of the gate bushing 16 extending over the adjacent edge of the heating chamber 2.

35. In the construction shown the carrier device 11 is provided with rollers 17 which are adapted to roll on horizontal tracks 18 formed on the upper side edges of the heating chamber 2. Rollers 17 may be mounted 40 on horizontal shafts or studs carried by the horizontal extensions 19, 19 at the front and rear of the carrier device. With the carrier device so mounted its nozzle or mouth 12 will be in horizontal alignment with the 45 bushing 16 formed in the plate 15.

The carrier device is provided at the rear with a bracket or extension 20. The heating chamber 2 is provided at the rear with a bracket 21 which carries a horizontal 50 shaft 22, which may be oscillated by means of the hand lever 23. Shaft 22 is connected to the rear extension 20 of the carrier device by a pair of toggle links 24, 25. The operation of the handle 23 serves to 55 straighten the toggle 24, 25, to force the delivery nozzle 12 into the gate opening in plate 15, and, on the opposite movement, to break the toggle and move the carrier device back into position in which nozzle 12 60 may be submerged within the molten metal in the melting pot.

The operation of our device will now be clear. The melting pot being in its raised position, a charge of molten metal will have 65 entered the carrier device through the nozzle

zle 12. Lever 10 is now thrown over to lower the melting pot so that nozzle 12 is uncovered by the molten metal, the upper edge of the melting pot dropping to a position slightly below the gate opening in 70 plate 15. Hand lever 23 is now depressed to straighten toggles 24, 25, and move the carrier device into its delivery position in which nozzle 12 is firmly inserted within the mouth of bushing 16. The carrier device is 75 locked in this position by the straightening of toggle links 24 and 25. The air pressure is then turned on in pipe connection 13 whereupon the charge in the carrier device will be forced through the bushing 16 into 80 the die. Lever 23 is then raised to move the carrier device back to its normal position, a stop being provided by the flange 26 on the rearward extension 20 of the carrier device, this flange 26 contacting against the 85 link 24 at the limit of movement of the carrier device to the right, referring to Fig. 1. Hand lever 10 is then swung into the vertical position to raise the melting pot so as to submerge nozzle 12 within the molten metal, the cycle of operations being repeated indefinitely.

It will be understood that our invention is not limited strictly to the details of construction described but is as broad as is indicated by the accompanying claims.

What we claim is:—

1. In casting apparatus, the combination of a molten metal container, a carrier device, having a delivery nozzle and a compressed gas connection, means for raising said container to submerge said nozzle in the molten metal, and for lowering the same, and means for moving said carrier device across said container, to and from position for delivering its charge of molten metal to a die.

2. In a casting apparatus, the combination of a molten metal container, a carrier device, adapted to deliver molten metal to a die and having an opening therein and a pressure connection, means for raising and lowering said container to submerge said opening in the molten metal and to bring the same above the surface thereof, and means for moving said carrier device across said container, to and from position for delivering its charge of molten metal to a die.

3. In casting apparatus, the combination of a molten metal container, a carrier device having a mouth and a pressure connection, means for causing relative vertical bodily movement between said container and device, to submerge said mouth in the molten metal and to bring the same above the surface thereof, and means for causing relative horizontal bodily movement between said container and device, when said mouth is above the surface of the metal, to place said mouth in position to deliver its charge

of molten metal to a die, and to place the same in position to be submerged within the molten metal, respectively.

4. In casting apparatus, the combination of a molten metal container, a carrier device having a mouth and a pressure connection, means for moving said device to and from position to deliver a charge of metal to a die, and means for raising and lowering said container, to submerge and uncover said mouth, comprising a lever and toggle joint.

5. In casting apparatus, in combination, a carrier device having a mouth and a pressure connection, a heating chamber, having vertical guideways therein, a molten metal container mounted therein, having projections slidably mounted in said guideways, a plunger supporting said container, extending out through the bottom of said chamber, means for raising and lowering said plunger to raise and lower said container with respect to said carrier device, and means for moving said carrier device with respect to said container to and from position to deliver the charge of metal to a die.

6. In casting apparatus, the combination of a support, tracks thereon, a carrier device having a nozzle, a pressure connection, and supporting means mounted on said

tracks, means for reciprocating said device upon said tracks comprising a shaft, means for oscillating the same and a toggle joint between said shaft and device, and a molten metal container so mounted in relation to said carrier device as to enable said nozzle to be submerged within and uncovered by the molten metal in said container.

7. In casting apparatus, the combination of a support, a molten metal container, a carrier device having a nozzle and a pressure connection, a track for movably supporting said device, means for causing said nozzle to be submerged within molten metal in said container and uncovered thereby, and means for moving said device forward and back across said container and locking it in forward position, consisting in a shaft mounted in said support, links pivotally connected to each other and to said device and shaft to constitute a toggle and means for straightening out and opening up the links constituting the toggle.

This specification signed and witnessed this 4th day of May, 1920.

JOHN KRÅLUND.
